ELECTRODYNAMIC RECORDING HEAD

Charles R. Douglass, Jr., Los Angeles, Calif.

Application August 25, 1947, Serial No. 770,368

4 Claims. (Cl. 179—100.41)

(Granted under the act of March 3, 1883, as
amended April 30, 1928; 370 O. G. 757)

1

This invention relates in general to transducers and more particularly to a recording head for the lateral cut disc type of phonograph record.

The recording head of this invention is of the magnetic type, but as distinguished from those of the prior art, it has only a fraction of the mass of those in common use. The discovery of the structure of this invention that enables a material reduction in the mass of the electromagnetic unit gives rise to a number of advantages of the unit of this invention over those of the prior art.

Accordingly, it is an object of this invention to provide a recording unit of the magnetic type in which the moving mechanism has a fraction of the mass of the moving mechanism of the magnetic recorders of the prior art.

Another object is to provide a recorder with a reduction in the inertia of the moving mechanism which results in the use of less stiff spring centering and return mechanism.

Another object is to provide a recorder with a moving mechanism that requires less damping and results in an overall increase in efficiency of the moving system.

Another object is to provide a recorder with a moving mechanism that displaces the mechanically resonant peak above the useful frequency range of the recording head.

Another object is to provide a recorder that has less transient distortion due to the reduction of inertia.

Another object is to provide a recorder in which the harmonic distortion has been reduced to a great degree over that present in magnetic recorders of the prior art.

Another object is to provide a hermetically sealed recorder in which fluid damping is utilized.

Another object is the provision of a recorder which will be economical to manufacture, reliable in operation and which possesses all of the qualities of ruggedness and dependability in service.

Figure 1 illustrates a front elevation view of the recording unit.

Figure 2 illustrates a side elevation view of the recording unit.

Figure 3 illustrates a plan view of the recording unit.

The recording head of this invention is of a different structure from that of any other recording head that has been used for the purpose of recording sound on disc. It embodies many improvements that have been made to overcome objections to the magnetic type of recording head.

The mass of the moving mechanism is only a fraction of the mass of the magnetic type head.

2

that is in common use. This reduction in mass, reduces the inertia of the moving system which results in the use of a much less stiff spring centering and return system. This reduction in mass, also reduces the amount of damping required which greatly increases the overall efficiency of the moving system. The use of this light moving system, displaces the mechanical resonant peak above the useful frequency range 10 of the recording head, and reduces the transient distortion by virtue of the reduction of the inertia of the moving parts.

Through the use of a moving coil as the actuating medium, the harmonic distortion is reduced to a great degree over that of the magnetic recording head, where magnetic saturation takes place in small moving armatures and pole-pieces. It is here pointed out, and will be described in detail later, that the type of moving coil used in the recording head of this invention is different from the moving coil of the prior art, and that it has several advantages over the conventional moving coil system.

The recording head of this invention is hermetically sealed and instead of using the conventional rubber or gelatin composition for a damping material, whose characteristics vary considerably due to temperature changes, a fluid is used for damping. This fluid is capable of 25 withstanding wide temperature variations without changing its viscosity. The case is filled to two-thirds of its height with fluid of proper viscosity to offer the required damping for proper recording response.

35. The main cutting needle actuating shaft 7 in Figure 2, projects out in front of the case, thereby allowing the cutting needle to operate in a position without obstructions on either side. This is an important advantage, for the vacuum shaving collection tube 20, which is used to pick up shaving 40 cut by needle 17, is mounted adjacent to the needle. This is an improvement that allows greater dependability in collecting this shaving, which has proven to be a hazard with recording heads of conventional construction, where the cutting needle projects from the bottom of the cutting head.

In many currently used recording heads the needle protrudes through the bottom of the case. 45. The needle is usually surrounded by a rubber washer whose purpose is to exclude foreign material from the opening. The foreign material is usually iron filings attracted by the magnetic field. This construction is not satisfactory, for 55 these small pieces of foreign material work up

into the opening during needle replacement. This difficulty is overcome in the recording head of this invention due to the needle chucking device being completely on the outside of the case.

Referring to Figures 1 to 3, the recording head receives its audio excitation from the proper source impedance or terminals 21. These exciting currents flow through coil 1 which is an extremely light insulating composition bobbin wound with the required number of turns of wire. This coil is oblong in shape as shown at 22, so that the greatest percentage of turns shall be in the magnetic field. There are two complete magnetic circuits, one generated by magnet 13 and one by magnet 14. The magnets are poled so that the flux paths 15 and 16 will be as shown, which will result in additive lateral forces being exerted by each side of coil 1. Coil 1 is mounted on aluminum alloy pins 6 which are supported by main drive shaft 7. Main drive shaft 7 is pivoted in two places by hardened steel wire pivot springs 8. Steel pivot springs 8 are imbedded firmly in cleats 9. This method of suspension in itself is unique, for the centering and stiffening springs 8 are used as the pivoting medium also. The length of springs 8 is adjusted during manufacture to offer the required mechanical stiffness to the moving system. The cutting needle 17 is chucked in the main shaft 7 by means of screw 26. The turning motions of the main shaft are hereby translated to lateral motions at the tip of the cutting needle 17, which further reduces the mass of the moving system by eliminating the usual heavy lower needle chucking device. The hermetic seal between the main shaft 7 and front plate 12 of the case is effected by a conical rubber gasket 10 which is at all times pressed in by spacing washer 27. All mechanism in the recording head is bolted to the front plate 12 which in turn is bolted to the cast aluminum case 11, mounted on the tone or carrying arm by the tapped holes 28.

A number of advantages have resulted in using the recording head of this invention. In the past several years, especially during war time, many thousands of hours of disk recording have been made both in the studio and in the field. Much difficulty has been encountered in recording high fidelity records, especially in the field. These difficulties can be traced primarily to the recording heads used. The heads used in the field in the past have suffered variations in frequency response and efficiency due to the wide range of temperature and humidity changes encountered. Furthermore, in order to record high fidelity with currently used recording heads, an audio amplifier power output of 50 watts is required. By using the recording head of this invention, high fidelity response can be had with a power output of 12 watts, which effects a desirable saving of weight in the portable recording units.

Through the use of hermetic sealing in the recording head of this invention, consistent high fidelity recording can be accomplished under conditions of varying temperature and humidity without danger of failure due to corrosion and fungus growths.

In operation, the currents varying in strength in accordance with the intelligence to be recorded are supplied through lead-in terminals 21, which conduct the currents to coil 1 where they set up a magnetic field whose strength varies proportionally to the strength of the currents. As pre-

viously pointed out, the permanent magnets are so poled as to produce the maximum amount of torque in the resulting reaction between the magnetic field of the permanent magnets and the magnetic field set up by the movable coil in response to the varying currents received. The reactions of the magnetic fields tend to displace the coil from the air gap of the magnets, first on one side and then on the other, depending upon whether the currents and the corresponding magnetic field produced thereby are increasing or decreasing. This developed torque tends to rotate the coil about a pivot formed by the springs 8, and it also rotates the cutting needle 17 about said pivot. It is clear that the tip of the needle has a lateral motion, the amplitude of which is proportional to the strength of the currents supplied. When the moving needle is imbedded in a moving record, it cuts a groove whose lateral variations are proportional to the variations of the currents supplied. If the supplied currents carry intelligence such as a speaking voice, the record so made by said currents will reproduce the voice upon reproduction as a phonograph record.

The novel structure set forth in this invention enables high fidelity recordings to be made under conditions where said recordings were unable to be made prior to this invention.

The invention described herein may be manufactured and used by or for the Government of the United States for governmental purposes without the payment to me of any royalties thereon or therefor.

What is claimed is:

1. In a transducer of the electromagnetic type having a moving mechanism of low mass for use in high fidelity recording comprising, a pair of magnets each having pole pieces positioned to form a centrally located airgap, said magnets having opposite poles adjacent each other, bridge members on both sides of one pair of opposite poles for spacing said magnets, a coil adapted to be energized by the signal to be recorded positioned in said airgap, a horizontally positioned shaft, support pins depending vertically from said coil, said support pins being rigidly attached at their other ends to the aforementioned shaft, vertically positioned spring pins mounted between said shaft and said bridge members, said spring pins acting as pivot mountings for said shaft, and means for mounting a stylus at one end of said shaft.

2. A transducer similar to that of claim 1, and a housing means enclosing said magnets, coil and shaft, said housing means having an opening therein through which the shaft supporting the stylus enters.

3. A transducer similar to that of claim 1, and a fluid-tight housing means completely enclosing said magnets, coil and shaft, said housing means having an opening therein through which the shaft supporting the stylus enters, said opening having a conical rubber gasket associated therewith to effect a hermetic seal between the shaft and the housing means, the housing means being filled with liquid to aid the damping of the said transducer.

4. In a transducer of the electromagnetic type having a moving mechanism of low mass for use in high fidelity recording comprising a pair of magnets each having pole pieces positioned to form a centrally located airgap, said magnets having opposite poles adjacent each other, bridge members on both sides of one pair of opposite

poles for spacing said magnets, an electrodynamic winding positioned in said airgap, a horizontally positioned shaft, supporting means for said winding located normal to said shaft and integral therewith, spring pins positioned parallel to said supporting means and integral with said shaft, said pins being rigidly attached to said bridge members for free movement of said shaft and winding, means at one end of said shaft for mounting a stylus, and a fluid tight housing means completely enclosing said magnets, winding and shaft, said housing means having an opening therein through which protrudes the end of said shaft to which the stylus is mounted, the housing means being filled with liquid to aid the damping of said transducer.
